FOLDABLE BED

George Isbell, Elkhart, and Eldon J. C. Rogers,
Huntington, Ind.; said Isbell assignor to said
Rogers

Application June 21, 1937, Serial No. 149,518

3 Claims. (Cl. 5—99)

The invention relates primarily to a child's bed which may be folded into compact form for packing and shipping, for carrying in an automobile or trailer, or for storage.

The principal object of the invention is to provide a new and improved construction which enables one person to quickly and easily fold the bed or unfold the same, without experiencing such difficulties and confusion as heretofore encountered with other folding beds.

A further object is to provide a construction which may be easily and inexpensively manufactured and may, therefore, be profitably sold at a reasonable price.

With the foregoing in view, the invention resides in the novel subject matter hereinafter described and claimed, description being accomplished by reference to the accompanying drawings.

Fig. 1 is a side elevation.

Fig. 2 is a top plan view.

Fig. 3 is a central vertical longitudinal section.

Figs. 4 and 5 are diagrammatic top plan views showing different steps in folding the bed.

Fig. 6 is a diagrammatic top plan view showing the bed completely folded.

Fig. 7 is a detail sectional view on line 7—7 of Fig. 2.

For convenience of description, the entire head of the bed has been denoted at 10, the foot at 11, one side at 12, the other side at 13, and the bottom or mattress support at 14. The shapes and designs of these various members may, of course, be varied within a wide range, and this is also true with regard to size and proportions.

The side 12 is composed of an inwardly swingable half 12^a hinged permanently to the head 10, a second inwardly swingable half 12^b hinged permanently to the foot 11, and hinges 15 permanently connecting said halves 12^a and 12^b with each other.

The side 13 is composed of a half 13^a permanently hinged to the head 10 to fold inwardly, a second inwardly foldable half 13^b permanently hinged to the foot 11, and means 16, 17 separately connecting said halves 13^a and 13^b with each other.

The bottom 14 is composed of one upwardly swingable half 14^a hinged to the head 10 and a second upwardly swingable half 14^b hinged to the foot 11.

When the bed is to be folded, one of the bottom halves (14^a, 14^b) may be upwardly folded and held with one hand while one of the separably connected side halves (13^a, 13^b) is folded in-

wardly against said bottom half with the other hand, whereupon said bottom section will be held in its upright position by said inwardly folded side half (Fig. 4). Then, the other bottom section may be upwardly swung with one hand and held by said hand while the other separably connected side half is swung inwardly against it, said other side half then holding said other bottom half in its upright position. Both hands are now free to handle the head 10 and foot 11 for the purpose of moving them toward each other after buckling the side 12 inwardly upon the hinges 15 (Fig. 5), the halves 12^a and 12^b of said side 12 then moving into positions between the previously folded halves 13^a and 13^b and the entire bed being thus in compact folded condition (Fig. 6). This folding, it will be observed, may be easily carried out by one person without difficulty or confusion, particular attention being invited to the fact that when 14^a is swung upwardly and 13^a swung inwardly against it, these parts will remain in their folded positions without being held, leaving both hands free to upwardly fold 14^b and inwardly fold 13^b, which parts will also remain in folded position without being held, leaving both hands again free for use when inwardly buckling the side 12 and moving the head and foot 10, 11 toward each other.

The head 10 and foot 11 each preferably consist of two corner posts 18 connected at their upper and lower portions by cross members 19 and 20, and appropriate uprights 21 extending between said members 19 and 20.

Each side (12 or 13) preferably includes an upper rail 22, a lower rail 23, and suitable uprights 24 extending between them. In alignment with these rails 22, 23, the posts 18 are provided with rigidly attached side rail stubs 24 and 25 respectively, to which the rails are hinged, the abutting ends of the rails and stubs being preferably beveled as shown at 26. In securing the stubs 24 and 25 to the posts 18, metal angle brackets 27 are employed, said brackets being secured by screws or the like to said posts and stubs and having horizontal arms 28 of flat form lying against the upper and lower edges of said stubs. Elongated metal hinge strips 29 are secured to the upper and lower edges of the side rails 22, 23 and project beyond these rails in overlapping relation with the flat arms 28 of the brackets 27, and rivets or the like 30 pass through the projecting ends of said strips 29, through said arms 28, and through the stubs 24, 25, thereby hingedly connecting the side halves 12^a, 12^b, 13^a and 13^b to the head 10 and foot 11. The

5 pivots 30 are so located as to prevent interference of any of the parts with each other when the bed is folded, in which connection, it will be observed that these pivots of the side halves 13^a and 13^b are much closer to the posts 18, than is true of the corresponding pivots of the side halves 12^a and 12^b.

10 The bottom halves 14^a and 14^b are connected by appropriate hinges 31 with the lower cross members 20 of the head 10 and foot 11, and the inner end portions of the side halves 12^a, 12^b, 13^a and 13^b, are provided with appropriate brackets 32 upon which the inner ends of said bottom halves 14^a and 14^b rest when in normal position.

15 These bottom halves are provided with downwardly projecting stubs 33 receivable in openings 34 (Fig. 7) of the brackets 32 and thus the sides 12 and 13 of the bed are so connected by the bottom 14 as to prevent lateral movements of 20 said sides. Lateral springing of the upper portions of the sides 12 and 13 is prevented by a pair of connecting plates 35 and 36 and details associated therewith, as now described.

25 The plate 36 forms part of the means 16, 17 for separably connecting the side halves 13^a and 13^b with each other, said plate being pivoted at one of its ends to the top rail of the half 13^b, as shown at 37 and extending into overlapping relation with the top rail of the other half 13^a.

30 This other half is provided with headed stubs 38 engageable with notches 39 in the lower edge of the plate 36, and the upper rail of the half 13^b which carries the pivot 31, is also preferably provided with a headed stub 40 receivable in 35 another notch 41 in the lower edge of the plate 36. The plate 35 is constructed and mounted in the same manner as the plate 36 and coacts with stubs similar to the stubs 38 and 40. It will thus be seen that the upper portions of the halves 40 12^a and 12^b and the upper portions of the halves 13^a and 13^b are effectively connected with each other in such manner that the side 12 and the side 13 cannot spring laterally at their upper portions. Plate 36 must, of course, be swung 45 free of the stubs 38 and 40 before the bed can be folded, and plate 35 must also be swung to released position.

50 The means 17 constituting part of the provision for separably connecting the halves 13^a and 13^b, preferably consists of an ordinary hook and eye, and we prefer that the lower rails 23 of said halves 13^a and 13^b be separably tongued and grooved as at 42 to coact with said hook and eye in establishing a proper connection between 55 the lower portions of the halves 13^a and 13^b. The hook must, of course, be disengaged from the eye before the bed can be folded.

60 When the entire structure is folded into the compact form shown in Fig. 6, the brackets 32 of the side halves 13^a and 13^b underlie the lower cross members 20 of the head and foot 10, 11, and the corresponding brackets of the side halves 12^a and 12^b then underlie said side halves 13^a and 13^b, and said brackets do not therefore interfere with folding of the structure into the most compact form.

65 Excellent results have been obtained from the details shown and described and they are therefore preferably followed. However, within the 70 scope of the invention as claimed, variations may

of course be made, the present disclosure being illustrative rather than limiting.

We claim:

1. A foldable bed comprising a head; a foot; one side composed of an inwardly-foldable half 5 hinged to said head, a second inwardly-foldable half hinged to said foot, and means permanently hinging said halves together; a second side composed of an inwardly-foldable half hinged to said head, a second inwardly-foldable half hinged 10 to said foot, and releasable means separably connecting these halves with each other; the halves of each side being of a length to overlap the halves of the other side when all of said halves are inwardly folded; and a bottom composed 15 of an upwardly-foldable half hinged to said head and a second upwardly-foldable half hinged to said foot; the hinge lines of said bottom halves being close to said head and foot to allow said bottom halves to fold compactly against said head 20 and foot, the hinge lines of said separably connected side halves being more distantly spaced from said head and foot to allow these halves to fold compactly against the upwardly folded bottom halves when disconnected, and the hinge lines 25 of said permanently connected side halves being still more distantly spaced from said head and foot to allow said permanently connected halves to be compactly folded against the inwardly folded separated halves; whereby after disconnection of said separably connected side halves, one of said bottom halves may be upwardly folded and held with one hand until the adjacent one of the disconnected side halves is folded inwardly against it with the other hand, 30 the other bottom half may then be likewise upwardly folded and held with one hand until the other of the disconnected side halves is folded inwardly against it with the other hand, and both hands are then free for moving the head 40 and foot toward each other after inwardly buckling the permanently connected side halves, these halves then moving to positions between the folded disconnected side halves.

2. A structure as specified in claim 1; the 45 inner end portions of all of said side halves being provided at their lower edges with brackets underlying said bottom halves, the brackets of the disconnected side halves being movable under portions of said head and foot when said disconnected side halves are folded, the brackets of the permanently connected side halves being movable under said folded disconnected halves.

3. In a foldable bed, a head and a foot each having corner posts, upper and lower side rail 55 stubs projecting from said corner posts, angle brackets secured to said corner posts and to said side rail stubs and having flat horizontal arms lying against the upper and lower edges of said side rail stubs, foldable sides having upper and lower side rails extending between the upper and lower side rail stubs of said head and foot, flat hinge strips secured upon the upper and lower edges of said side rails and projecting therefrom into overlapped relation with said flat horizontal bracket arms, and pivots connecting the projecting ends of said hinge strips with said bracket arms.

GEORGE ISBELL.

ELDON J. C. ROGERS.
